(57) **CLAIM**

The ornamental design for a garment hanger with under notches as shown and described.

DESCRIPTION

FIG. 1 is a perspective view of a garment hanger with under notches showing our new design;
FIG. 2 is a second perspective view thereof;
FIG. 3 is a front elevation view thereof;
FIG. 4 is a rear elevation view thereof;
FIG. 5 is a partial sectional view taken along lines 5-5 shown in FIG. 4;
FIG. 6 is a partial sectional view taken along lines 6-6 shown in FIG. 4;
FIG. 7 is a partial sectional view taken along lines 7-7 shown in FIG. 4;
FIG. 8 is a top plan view of FIG. 1;
FIG. 9 is a bottom plan view thereof; and,
FIG. 10 is a side elevation view thereof, and the opposite side elevation view is a mirror image thereof.
The short dash-long dash lines shown in FIG. 4 represent the planes upon which the sectional views are taken and form no part of the claimed design.
